UNITED STATES PATENT OFFICE

2,597,403

INTERRUPTED THREAD TYPE SLIDABLE
JAW WRENCH

John T. Tedesco, Bronx, N. Y.

Application May 20, 1948, Serial No. 28,172

2 Claims. (Cl. 81—159)

1

This invention relates to an interrupted thread type, slidable jaw wrench.

More particularly, it relates to a wrench of the type referred to which can be applied to various size nuts with a minimum of effort and time.

An object of the present invention is to provide an adjustable wrench for application to various size nuts or bolts, which wrench can be adjusted by a sliding motion of one jaw and tightened by a short rotary motion of another part of the wrench, thereby doing away with the necessity of a long rotary operation to adjust one jaw of the wrench relative to the other jaw.

A further object is to provide a wrench as aforesaid of the type adapted to receive the bolt or nut through one open end of the jaws.

A further object is to provide a wrench of the aforesaid type wherein the bolt or nut is received in an adjustable socket.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a wrench constructed in accordance with this invention.

Fig. 2 is a longitudinal sectional view of the wrench shown in Fig. 1.

Fig. 3 is an enlarged sectional view taken on the line 3—3 of Fig. 2.

Fig. 4 is a partial perspective view of one member of the wrench shown in Fig. 1.

Fig. 5 is a longitudinal sectional view similar to Fig. 2, but illustrating a modification of the invention.

Fig. 6 is an enlarged sectional view taken on the line 6—6 of Fig. 5.

Fig. 7 is a longitudinal sectional view of a wrench constructed in accordance with a still further modification of the invention.

Fig. 8 is an enlarged sectional view taken on the line 8—8 of Fig. 7.

Fig. 9 is a longitudinal sectional view of a wrench constructed in accordance with still another modification of the invention.

Fig. 10 is a sectional view taken on the line 10—10 of Fig. 9.

Fig. 11 is a partial perspective view of one of the jaw members used in the form of the invention shown in Fig. 9.

Fig. 12 is a perspective view of the other jaw

2

member used in the form of the invention shown in Fig. 9.

Fig. 13 is a partial longitudinal sectional view of a wrench constructed in accordance with still another modification of the invention.

Fig. 14 is an enlarged longitudinal sectional view of the handle end of the wrench shown in Fig. 13.

Fig. 15 is an enlarged detailed view of a portion of Fig. 14.

Fig. 16 is a sectional view on the line 16—16 of Fig. 14.

Fig. 17 is a side elevational view of a wrench constructed in accordance with a further modification of the invention.

Fig. 18 is an enlarged sectional view on the line 18—18 of Fig. 17.

Fig. 19 is a side elevational view of a still further modification of the wrench.

Fig. 20 is an enlarged sectional view taken on the line 20—20 of Fig. 19.

Fig. 21 is a sectional view taken on the line 21—21 of Fig. 20.

Fig. 22 is a side elevational view of a wrench constructed in accordance with a further modification of the invention.

Fig. 23 is an enlarged longitudinal sectional view of a portion of the wrench shown in Fig. 22.

Fig. 24 is an enlarged detailed view of a portion of Fig. 23.

Fig. 25 is a sectional view taken on the line 25—25 of Fig. 23.

Fig. 26 is an elevational view of a still further modification of the wrench.

Fig. 27 is a partial longitudinal sectional view of the wrench shown in Fig. 26.

Fig. 28 is an enlarged sectional view taken on the line 28—28 of Fig. 27.

Fig. 29 is a view similar to Fig. 26, but illustrating a further modification of the invention.

The wrench disclosed in Figs. 1 to 4 comprises a handle 10 consisting of a tubular handle portion 11 and a rotative handle portion 12. A fixed jaw member 13 is mounted on one end of the tubular handle portion 11. The fixed jaw member 13 is sweated onto the tubular handle portion 11 or it may be welded, brazed or in any other manner securely attached in position.

The rotative handle portion 12 is disposed within the tubular handle portion 11, and is formed at the end of the tubular handle portion 11 adjacent the fixed jaw member 13, with an enlarged head 14 which prevents the rotative handle portion 12 from being withdrawn from the tubular handle portion 11. The opposite

end of the rotative handle portion 12 is formed with a knurled extension 15 by which the rotative handle portion 11 may be conveniently rotated. As shown the knurled extension projects beyond the end of the tubular handle portion 11 in abutting end relationship, and in assembling the handle portions 11 and 12, the handle portion 12 is inserted into the tubular handle portion 11 from the end opposite the fixed jaw member 13 and the head 14 is formed on the inserted end of the rotative handle portion 12.

An intermediate area of the rotative handle portion 12 is knurled, as indicated at 16, and the knurled area is in alignment with diametrically opposite openings 17 formed in the sides of the tubular handle portion 11. In using the wrench, fingers can be inserted through the openings 17 to contact the knurling 16 to facilitate rotation of the rotative handle portion 12 from that area of the tubular handle portion 11.

A movable jaw member 18 has one end inserted into the tubular handle portion 11 through a longitudinal slot 19 formed in one side of the tubular handle portion. The inserted end of the movable jaw member 18 is formed with an opening engaged about a reduced threaded end 12^a formed on the rotative handle portion 12. The reduced threaded end is formed with flat sides 12^b (see Figs. 3 and 4). At diametrically opposite sides the movable jaw member 18 is formed with inwardly directed threaded areas 18^a, which are selectively engaged with the threads of the threaded end 12^a of the rotative handle portion 12 or disengageable from those threads as shown in Fig. 3.

The flat sides 12^b on the rotative handle portion 12 interrupt the continuous nature of the thread on the threaded end 12^a of the handle portion 12, and when the threads are disengaged as shown in Fig. 3, the movable jaw member 18 is free to be easily moved longitudinally of the handle 10 relative to the fixed jaw member 13. A 90 degree turn of the rotative handle portion 12 from the position shown in Fig. 3 will engage the threads on the movable jaw and the threaded end 12^a of the handle locking the movable jaw 18 in a desired fixed position.

The method of using the wrench shown in Figs. 1 to 4 is as follows:

With the threads 18^a on the movable jaw member 18 disengaged from the threads on the threaded end 12^a of the rotative handle 12, the fixed jaw member 13 is engaged against one side of the object it is desired to tighten or loosen, and the movable jaw 18 is slid along the length of the slot 19 to a position engaging the opposite side of the object. The rotative handle portion 12 is given a quarter turn to engage the threads 18^a of the movable jaw with the threads on the threaded end 12^a of the handle portion 12 to lock the movable jaw member 18 in position. The wrench is then used in the customary fashion to tighten or loosen the object upon which it has been engaged.

To remove the wrench from the object, the above procedure is reversed. It will be understood that the present invention provides a wrench which can be quickly adjusted to receive objects; such as, nuts, bolts, pipes, and the like, with a minimum of time and a minimum of turning action.

In Figs. 5 and 6, a modification of the wrench is disclosed, in which the movable jaw 18' is engaged about the outside of the tubular handle

portion 11, and is formed with diametrically opposite inwardly extended lugs 20 extended into the interior of the tubular handle portion 11 through diametrically opposite slots 19' formed in the handle portion 11. The inner ends of the lugs 20 are formed with the threads 18^a engageable and disengageable with the threaded end 12^a of the rotative handle portion 12. The lugs 20 are securely welded in position within complementary recesses 21 formed in diametrically opposite sides of the movable jaw 18'.

In other respects this form of the invention is similar to that previously described, and like reference numerals identify like parts in all the views.

In Figs. 7 and 8 another modification of the invention is shown in which a handle 30 consists of a fixed handle portion 31 and a rotative handle portion 32. The rotative handle portion 32 is tubular and the fixed handle portion 31 is extended through the tubular handle portion 32. One end of the fixed handle portion 31 extends from the adjacent end of the movable handle portion 32 as a knurled grip 33, and the other end of the fixed handle portion 31 extends from its adjacent end of the movable handle portion 32 and has mounted thereon a fixed jaw member 34.

A pin 35 extends through the movable handle portion 32 and extends into a groove 36 formed in the fixed handle portion 31 for rotatively retaining the movable handle portion in a fixed rotative position adjacent the knurled grip 33 of the fixed handle portion 31.

A movable jaw member 37 is slidably disposed on the fixed handle portion 31 and is formed with a socket opening 38 into which the adjacent end of the movable handle portion 32 extends. Diametrically opposite sides of the inserted end of the movable handle portion 32 are formed with spaced threads 32^a between flat sides 32^b. The threads 32^a are selectively engageable with and disengageable from complementary threads 37^a formed on the movable jaw member 37 within the socket opening 38.

With the complementary threads 32^a and 37^a engaged as shown on the drawings, the movable jaw 37 will be locked in a fixed position relative to the fixed jaw 34. However, if the movable handle portion 32 is given a quarter turn, the threads 32^a and 37^a will be disengaged and the movable jaw portion 37 will be free to be slid to any desired position relative to the fixed jaw member 34.

In the modification of the invention shown in Figs. 9 to 12, the wrench comprises a handle 40 having its end 40^a knurled, to better adapt it for gripping. The opposite end 40^b of the handle is reduced and passed through an opening 41 formed in a fixed jaw member 42. The end 40^b is milled over after being inserted into the opening 41 to retain the fixed jaw in position on the end of the handle, but it is pointed out that the handle 40 is free to be rotated relative to the fixed jaw member 42.

A movable jaw member 43 has a portion 43^a received within a socket opening 42^a formed in the fixed jaw 42. The portion 43^a continues into an intermediate portion 43^b extended through a passage 42^b formed in the side of the fixed jaw member 42 opposite its jaw element 42^c. The intermediate portion 43^b of the movable jaw member 43 in turn continues into a jaw element 43^c which is adapted to cooperate with the jaw ele-

ment 42^c of the fixed jaw member 42 in clamping an object to be tightened or loosened.

The handle 40 passes through an opening formed in the portion 43^a of the movable jaw member 43 and that area of the handle 40 is formed with spaced threads 40^c between flat sides 40^b. The opening in the portion 43^a of the movable jaw member 43 is formed with spaced threads 43^c selectively engageable with and disengageable from the threads 40^c of the handle 40. When the threads are engaged the movable jaw member 43 is locked in position, but when the threads are disengaged, as shown in Figs. 9 and 10, the movable jaw member 43 is free to be moved longitudinally relative to the fixed jaw member 42.

In Figs. 13 to 16 of the drawings, another modification of the invention is disclosed in which a fixed jaw member 50 is formed integrally with a tubular shank 51. A movable jaw member 52 is formed on the end of a stem 53 which extends through the fixed jaw 50 and the tubular shank 51. A pin 54 is extended through one side of the tubular shank 51 and extends into a longitudinal groove 55 milled in the side of the stem 53 to limit the stem 53 to longitudinal sliding movement only relative to the tubular shank 51.

A rotative handle portion 56 forms an extension of the tubular shank 51 and engages over the end of the stem 53 which projects from the end of the tubular shank 51. A collar 57 is threadedly engaged upon the end of the tubular shank 51 and has an inwardly directed flange 57^a which engages an outwardly directed flange 56^a for rotatively connecting the handle portion 56 to the shank 51.

Within the rotative handle portion 56, the stem 53 is formed with threads 53^a separated by diametrically opposite flat sides 53^b formed on the stem 53. The interior of the rotative handle 56 is formed with diametrically opposite threads 56^b which are selectively engageable and disengageable with the threads 53^a formed on the stem 53. With the threads 53^a and 56^b engaged as shown in Figs. 14 and 16, the stem 53 and in turn the movable jaw member 52 will be locked in position relative to the fixed jaw member 50. In a ninety degree turned position of the rotative handle portion 56, the threads 53^a and 56^b will be disengaged freeing the stem 53 to be slid longitudinally in the shank 51 to adjust the position of the movable jaw member 52 relative to the fixed jaw member 50.

In the modification of the invention disclosed in Figs. 17 and 18, the fixed jaw 60 is mounted on one end of a handle 61 formed at its other end with an enlarged gripping portion 62. A movable jaw 63 is slidable on the handle 61 between the fixed jaw 60 and the enlarged gripping portion 62. A bushing 64 is rotatively disposed in an opening 66 formed in the movable jaw 63 and is rotatively retained in position by a pin 65 extended in from one end of the movable jaw member 63.

The bushing 64 is located along one side of the handle 61 and is formed with threads 64^a and a flat side 64^b. The threads 64^a of the bushing 64 are selectively engageable with and disengageable from complementary threads 61^a formed along the adjacent side of the handle 61.

When the threads 61^a and 64^a are engaged as shown on the drawings, the movable jaw member 63 will be locked against movement relative to the fixed jaw member 60. However, when the bushing 64 is rotated to align its flat side 64^b with

the threads 61^a on the handle 61, the movable jaw member 63 will be free to move on the handle 61 to desired adjusted position relative to the fixed jaw 60.

If desired, the end of the pin 65 may be provided with a suitable handle or knob by which the pin may be rotated for turning the bushing 64 for engaging and disengaging its threads 64^a with the threads 61^a on the side of the handle 61. 10 If the pin 65 is provided with such a handle or knob, it is appreciated that the bushing 64 will have to be securely attached to the pin 65.

The modification of the invention shown in Figs. 19 to 21 is somewhat similar to that shown in Figs. 17 and 18. In this form of the invention an expansion spring 70 is mounted on the handle 61' and operates between the end of the movable jaw member 63' and the gripping portion 62 of the handle 61' for normally urging the movable jaw member 63' toward the fixed jaw member 60, in the freed position of the movable jaw member.

Also, in this form of the invention there is a modified construction for locking the movable jaw 63' in position relative to the fixed jaw 60. In this form of the invention, the handle 61' is formed with a projecting ledge 71 formed with serrations 71^a, and the adjacent wall of the movable jaw member 63' is formed with a cutout 72 20 which houses a slide 73 for movement toward and away from the serrations 71^a of the ledge 71.

Means is provided for moving the slide 73 to engage serrations 73^a, formed thereon, with and disengage them from the serrations 71^a. This 35 means comprises a stud shaft 74 extended through the movable jaw member 63' and formed at its outer end with a small handle 75 by which the stud shaft 74 can be rotated. A disc 76 is eccentrically mounted on the inner end of the stud shaft 74 and is disposed in a cam opening 77 40 formed in the slide 73. In one rotative position of the disc 76, the slide will be in the position shown on the drawings, see Fig. 21, in which the serrations 73^a on the slide 73 will be engaged with the serrations 71^a on the ledge 71 of the handle 61' for locking the movable jaw member 63' in position relative to the fixed jaw member 60. In a 180 degree turned position of the disc 76, the slide 73 will be moved from the position shown 45 in the drawings, to a position in which the serrations 73^a and 71^a will be disengaged freeing the movable jaw member 63' to be moved relative to the fixed jaw member 60.

In the disengaged position of the serrations 71^a and 73^a, the spring 70 will act to urge the jaw members 60 and 63' into facial contact or to urge the movable jaw member 63' into contact with an object inserted between the jaw members.

In Figs. 22 to 25, the modified wrench comprises a fixed handle 80 having a fixed jaw member 81 attached to one end and provided at the other end with a knurled grip 82. A movable jaw member 83 is slidable on the handle 80, and the 60 portion of the handle 80 engaged by the movable jaw member 83 is of configuration, e. g. square or hexagonal, to hold the movable jaw member 83 against rotation on the handle.

A rotative handle 84 is rotatively attached to 65 the rear end of the movable jaw member 83, and the rotative connection is accomplished by a collar 85 which is threadedly engaged into the end of the movable jaw member 83. The collar 85 has an inwardly directed flange 85^a cooperating 70 with the outwardly directed flange 84^a on the ro-

tative handle 84 to rotatively retain the handle 84 in position.

Internally, the rotative handle 84 is formed with spaced threads 84^b. The immediate area of the handle 80 is formed with diametrically opposite flat sides 80^a separating threads 80^b. The threads 80^b of the handle 80 when separated from the threads 84^b on the rotative handle 84, leave the handle 84 free to be moved longitudinally to similarly move the movable jaw member 83 relative to the fixed jaw member 81. Engagement of the threads 80^b and 84^b, in their rotative positions of the rotative handle 84, locks the movable jaw member 83 in a fixed position relative to the fixed jaw member 81.

In Figs. 26 to 28 a still further modification of the invention is disclosed comprising a fixed jaw member 90 in the form of a frame adapted to be engaged about a hexagonal bolt, nut or similar hexagonal member. A handle 91 is integrally formed with the fixed jaw member and extends laterally from one side thereof.

A movable jaw member 92 is disposed within the frame forming the fixed jaw member 90, and novel means is provided for slidably supporting the movable jaw member.

The fixed jaw member 90 is formed with an opening 93 in which is disposed a ring 94 which has its outer periphery knurled. The movable jaw member 92 is formed with a stem 96 which extends through the ring 94 and into a recess 97 formed in the handle 91.

As shown in Fig. 28, the interior of the ring 94 is formed with spaced threads 94^a cooperative with spaced threads 96^a formed on the stem 96 to hold the stem 96 and the movable jaw member 92 against movement relative to the fixed jaw member 90. The threads 96^a on the stem 96 are separated by flat sides 96^b formed on the stem, and when the ring 94 is rotated through 90 degrees to disengage the threads 94^a and 96^a and to align the threads 94^a of the ring 94 with the flat sides 96^b on the stem 96, the stem will be free permitting its longitudinal movement to similarly move the movable jaw member 92.

In Fig. 29 a further modification of the invention is disclosed, which is similar to that shown in Figs. 26 to 28, differing merely in the formation of the movable jaw member 92'.

In this form of the invention, the movable jaw member 92' is formed with a V-shaped recess 100 arranged to cooperate with the fixed jaw 90 in gripping a square bolt head, nut or similar square object indicated by the dot and dash lines 101.

In other respects this form of the invention is similar to that disclosed in Figs. 26 to 28, and like reference numerals identify like parts in the several views.

In all forms of the invention illustrated, the sliding parts are all formed with cooperating pairs of flat surfaces; however, if desired they may be provided with single flat surfaces. Also, all cooperating threads may be single or plural threads, and preferably the ends of the threads at the sides of the flat surfaces should be beveled for guiding the engagement of the threads when the parts are moved from positions in which the threads are disengaged to positions in which the threads are engaged.

While I have illustrated and described the preferred embodiments of my invention, it is to be understood that I do not limit myself to the precise constructions herein disclosed and the right

is reserved to all changes and modifications coming within the scope of the invention as defined in the appended claims.

Having thus described my invention, what I claim as new and desire to secure by United States Letters Patent is:

1. A wrench comprising a fixed jaw having an extension projecting from its side opposed to its gripping surface and a passage in one end thereof, said extension having a socket opening extended in from the side thereof adjacent the said one end of said fixed jaw and communicating with said passage, an elongated handle having one end portion extended through said socket opening and rotatively connected with said fixed jaw, a movable jaw having a jaw element facing the gripping surface of said fixed jaw and a tubular portion slidably fitted into said socket opening and encircling the said one end portion of said handle, said tubular portion and the said one end portion of said handle having threads for moving said movable jaw relative to said fixed jaw, said movable jaw having an intermediate portion between its jaw element, said tubular portion extended slidably through said passage retaining said movable jaw to have sliding movements only relative to said fixed jaw in a plane parallel to the axis of said handle.

2. A wrench comprising a fixed jaw having an extension projecting from its side opposed to its gripping surface and a passage in one end thereof, said extension having a socket opening extended in from the side thereof adjacent the said one end of said fixed jaw and communicating with said passage, an elongated handle having one end portion extended through said socket opening and rotatively connected with said fixed jaw, a movable jaw having a jaw element facing the gripping surface of said fixed jaw and a tubular portion slidably fitted into said socket opening and encircling the said one end portion of said handle, said tubular portion and the said one end portion of said handle having threads for moving said movable jaw relative to said fixed jaw, said movable jaw having an intermediate portion between its jaw element, said tubular portion extended slidably through said passage retaining said movable jaw to have sliding movements only relative to said fixed jaw in a plane parallel to the axis of said handle, said threads being circumferentially interrupted to be engaged and disengaged by rotative movement of said handle relative to said tubular portion.

JOHN T. TEDESCO.
